United States Patent Office.

V. M. BAKER, OF PRESTON, MINNESOTA.

Letters Patent No. 90,419, dated May 25, 1869.

IMPROVEMENT IN TURBINE-WHEELS.

The Schedule referred to in these Letters Patent and making part of the same.

To all whom it may concern:

Be it known that I, V. M. BAKER, of Preston, in the county of Fillmore, and State of Minnesota, have invented a new and improved Turbine Water-Wheel; and I do hereby declare that the following is a full, clear, and exact description thereof, which will enable others skilled in the art to make and use the same, reference being had to the accompanying drawings, forming part of this specification.

Figure 1 is a top view of my improved water-wheel.

Figure 2 is a side view of the same, part being broken away to show the construction.

Figure 3 is a detail horizontal section of the same, taken through the line $x\ x$, fig. 2.

Figure 4 is a detail sectional view of the same, taken through the line $y\ y$, fig. 3.

Figure 5 is a top view of the box for supporting the shaft, the top plate being removed.

Figure 6 is a detail sectional view of the same, taken through the line $z\ z$, fig. 5.

Similar letters of reference indicate corresponding parts.

My invention has for its object to improve the construction of water-wheels, so as to make them more effective and convenient in use, enabling them to utilize a larger per cent. of the power of the water, and to be more conveniently operated, than when constructed in the ordinary manner.

And it consists in the construction and combination of the various parts, as hereinafter more fully described.

A is the shaft, to which the wheel is attached, the lower end of which revolves in a step, B, and which passes up through the box C, attached to the upper part of the cap-plate d of the outer case D.

In the box C are placed two blocks E, the concave faces of which, or ribs formed upon said concave faces, enter a circular groove formed around the shaft A, so that the weight of the shaft and wheel may be partially supported by said blocks and box.

The blocks E are moved up to the shaft A, to compensate for wear, by set-screws F passing in through the sides of the box C, and the forward ends of which rest against the said blocks E, as shown in figs. 5 and 6.

G is a tube, through which the shaft A passes, and upon the lower end of which is formed, or to it is attached, a flange, g , fitting upon and forming the top plate of the box C.

H is the wheel, which is made with long buckets h^1 , and short buckets h^2 , connected together at the lower ends of the short buckets h^2 .

The long buckets h^1 are made thick at their outer edge, where they connect with the short buckets h^2 , so that the water may be carried to the lower or curved parts of the buckets h^1 , without loss of power from friction.

The buckets h^1 , from their points of connection with the short buckets h^2 , are made upon a true curve.

By this construction and arrangement of the buckets h^1 h^2 , the direct and reacting forces of the water are utilized to a much greater extent than is possible with water-wheels otherwise constructed.

D is the outer or stationary case of the wheel, in the upper part of which are formed the chutes I, by which, and the gates J, the water is conducted to the wheel H.

The gates J are formed as shown in fig. 3.

The inner plates of the gates J are curved inward at their forward ends, so that as the said gates are hoisted or opened, their forward edges may keep close to the face of the wheel H, so as to insure the passage of all the water from the chute to the wheel, thus preventing loss of power from some of the water escaping between the chute and wheel, as it would otherwise be liable to do.

The outer plates of the gates J are made curved, as shown in fig. 3, so that the said gates, in connection with the chutes I, may conduct the water to the wheel with the least possible amount of friction.

The gates J are kept in proper position by guide-flanges or ways d^2 , as shown in fig. 3.

K is a ring-plate, to the centre of the cross-arm of which is attached a sleeve, k' , fitting upon the tube G.

Through the plate K are formed slots to receive the upper ends of the levers L, where they are secured in place by the short levers or hooks M, as shown in figs. 1 and 2.

The levers L are pivoted to supports N, attached to the outer case D, and their lower ends enter sockets j' , formed in or attached to the gates J, so that the said gates may be opened and closed by operating the ring-plate K.

To the lower ends of the levers L are pivoted small wheels, O, to diminish the friction in operating the gates J, as shown in fig. 2.

To one side of the ring-plate K is attached, or upon it is formed, a rack, P, into the teeth of which mesh the teeth of the small wheel Q attached to the shaft R. The shaft R revolves in bearings attached to the case D, and motion may be given to it, to operate the gates J, by a crank or other convenient means.

Having thus described my invention,

I claim as new, and desire to secure by Letters Patent—

1. The tube G, having a flange, g , upon its lower end, to serve as a cap for the box C, in combination with the box C, ring-plate K, and shaft A, substantially as herein shown and described, and for the purposes set forth.

2. The gates J, constructed, arranged, and operating in connection with the wheel H and chutes I, substantially as herein shown and described, and for the purpose set forth.

3. The long levers L, short or hook-levers M,

and ring-plate K, in combination with each other and with the gates J and case D, substantially as herein shown and described, and for the purpose set forth.

4. The buckets h^1 h^2 , constructed, arranged, and operating substantially as herein shown and described, and for the purpose set forth.

5. The combination of the box O and adjustable

blocks E, with the grooved shaft A and case D, substantially as herein shown and described, and for the purpose set forth.

V. M. BAKER.
